DESIGN FOR A CYCLE SADDLE

Eli W. Gaffield, Washington, D. C., assignor of
ten per cent to Jouett Shouse, Washington,
D. C.

Application November 18, 1948, Serial No. 149,697

Term of patent 14 years

(Cl. D90—16)

To all whom it may concern:

Be it known that I, Eli W. Gaffield, a citizen of the United States, residing at Washington, in the District of Columbia, have invented a new, original, and ornamental Design for Cycle Saddles, of which the following is a specification, reference being had to the accompanying drawing, forming a part thereof.

In the drawing,

Figure 1 is a side elevation of the cycle saddle, showing my new design;

Figure 2 is a rear elevation thereof; and

Figure 3 is a top plan view of the same.

I claim:

The ornamental design for a cycle saddle, as shown.

ELI W. GAFFIELD.
